Primary Examiner — Selina Sikder

CLAIM

The ornamental design for a skull-shaped switch, as shown and described.

DESCRIPTION

FIG. 1 is a front elevation of the skull-shaped switch showing our new design;

FIG. 2 is a back elevation view thereof;

FIG. 3 is a left elevation view thereof;

FIG. 4 is a right elevation view thereof;

FIG. 5 is a top view thereof;

FIG. 6 is a bottom view thereof;

FIG. 7 is a perspective view thereof;

FIG. 8 is another perspective view thereof;

FIG. 9 is another perspective view thereof; and,

FIG. 10 is another perspective view thereof.
